UNITED STATES PATENT OFFICE.

JOHN STEWART WOOD, OF WALTON-UPON-THAMES, ENGLAND.

SEAT-SPRING.

SPECIFICATION forming part of Letters Patent No. 593,631, dated November 16, 1897.

Application filed December 11, 1896. Serial No. 615,319. (No model.)

To all whom it may concern:

Be it known that I, JOHN STEWART WOOD, a member of the Royal College of Veterinary Surgeons, a subject of the Queen of Great Britain, residing at Atherstone, Walton-upon-Thames, in the county of Surrey, England, have invented a certain new and useful Improvement in Seat-Springs, of which the following is a specification, reference being had

10 to the accompanying drawings, and to the letters marked thereon—that is to say:

The invention relates to a spring-support applicable for various useful purposes—such, for example, as a support for the seats, saddles, or bodies of velocipedes or other road-carriages, tram-cars, railway-carriages, or the like—and has for its object to obtain a spring-support of a novel character possessing great elasticity and the strength or resistance of 20 which is capable of being regulated according to the load to be carried, as hereinafter described and claimed.

In the accompanying drawings, Figure 1 is a side elevation representing a spring-support constructed according to the present invention. Fig. 2 is an end elevation thereof. Fig. 3 is a plan of the spring-cylinder separately. Fig. 4 is a vertical longitudinal section of the spring-cylinder separately, and 30 Fig. 5 is a transverse section taken on the line 5-5 of Fig. 4.

In the several figures like parts are indicated by similar letters of reference.

Referring to Figs. 1 to 5, *a* represents a 35 short horizontal bar formed tubular, which constitutes the base of the device, and at a suitable distance above the base-bar *a* is provided a corresponding bar *b*, which is supported upon the upper ends of two pairs of 40 links *c*, pivotally connected at *c'* with studs or offsets *a'* *b'* from the bars *a* and *b*, while in order to render the base *a* of sufficient width to give a steady support to the upper bar *b* the studs or offsets *a'* at one end of the 45 base-bar *a* are formed of greater length than the upper studs *b'*, and the links *c* are bent or cranked accordingly, as shown more particularly at Fig. 2. The frame thus formed assumes approximately the figure of a diamond and its movement is similar to that of a parallel-ruler, and within this diamond and 50 extending diagonally from one end of one

horizontal bar *b* to the opposite end of the other horizontal bar *a* is a rod or link *d*, which at one end is pivotally connected, by means 55 of a slotted lug *d'* thereon, with a corresponding lug *b'*, fixed to the adjacent horizontal bar *b*. The other end of the rod or link is connected to a lug *d''*, working in the slot *d'* and fixed with a piston *d'''* located within the 60 tubular bar *a*, as hereinafter described.

d'' is a spring which is inclosed within the tubular base-bar *a* and acts against the piston *d'''*, which is formed of considerable length, so that it will not be liable to bind in the 65 tubular bar *a*, and the regulating-piston *d''* is centrally apertured and threaded to engage a screw-thread *d'''* upon a rod *d''*, which is mounted with capability of revolving in a bearing *d''* in the end *d''* of the tubular bar *a*, 70 and the strength or degree of compression of the spring *d''* may be regulated by turning with a spanner the square *d''*, and thereby traversing the piston *d'''*.

As an example of the method of fixing the 75 spring-support with its frame or holder and with the load or object to be carried, the device shown may be provided with lugs *g*, as shown by the dotted lines.

The device hereinbefore described may be 80 usefully employed as a spring-support for the seats of velocipedes, railway or other carriages, tram-cars, or the like, or for the bodies of carriages or in other situations where other kinds of springs are now used.

When lightness is an object, the device may 85 with advantage be constructed of aluminium.

By the means hereinbefore described a spring-support is obtained which will materially assist to lessen the transmission of shocks 90 or vibrations.

Although the arrangements hereinbefore described represent the preferred forms of the device at the present time, it will be obvious that the details and arrangement of the 95 parts may be more or less varied without departing from the spirit of the invention.

Having now particularly described and ascertained the nature of the said invention and in what manner the same is to be performed, 100 I declare that what I claim is—

A spring-support comprising two parallel bars arranged one above the other, and pivotally connected by links arranged at an an-

gle to the bars, the device assuming approximately the figure of a diamond, a bar arranged diagonally within the diamond, and at one end flexibly connected with the extremity of one of the parallel bars, a piston inclosed within the other parallel bar, and flexibly connected with the diagonal bar, a coiled spring for acting upon the piston so that the force of the spring tends to bring the links to a vertical position, and to resist the elongation of the diamond, a movable abut-

ment for the spring, a screw-threaded aperture in the abutment, and a screw engaging such thread and on the exterior of the bar or tube provided with a square or other means ¹⁵ for turning the screw and regulating the spring substantially as herein shown and described and for the purpose stated.

JOHN STEWART WOOD.
